AUXILIARY SPARK IGNITION APPARATUS
FOR INTERNAL COMBUSTION ENGINESIvan Jack Hulbert, Willesden Junction, London,
England, assignor to Rotax Limited, London,
EnglandApplication June 11, 1943, Serial No. 490,508
In Great Britain June 17, 1942

2 Claims. (Cl. 123—148)

This invention relates to auxiliary spark ignition apparatus for internal combustion engines, the apparatus being of the kind used in conjunction with a magneto for starting an engine and comprising a transformer having a trembler interrupter in its primary circuit and having its secondary winding adapted to be connected to the primary winding of the magneto.

The invention has for its object to provide an improved auxiliary apparatus of the kind aforesaid, which is adapted to be kept in action even when the engine is running at a considerable speed and without detriment to the normal action of the magneto.

The invention comprises the combination of a primary winding, a secondary winding, and a pair of trembler interrupters respectively adapted to control the circuits containing the primary and secondary windings.

In the accompanying sheet of explanatory diagrams, Figures 1 and 2 illustrate one mode of carrying the invention into effect, Figure 1 serving to elucidate the circuits shown in Figure 2.

In the diagrams *a* indicates the primary winding and *b* the secondary winding of a magneto having a cam-operated interrupter *c* across which is arranged the usual condenser *d*. The primary winding *a* of the magneto is adapted to be connected to the secondary winding *e* of a transformer having a primary winding *f*, the latter being adapted to be connected to a storage battery or other source of current supply *g* through a controlling switch *l*.

In carrying the invention into effect as shown, I mount the primary and secondary windings *f*, *e* of the transformer on an iron core *h*, and in association with the core are arranged a pair of trembler interrupters *i*, *j* adapted to respond to the magnetic attraction of the core. The interrupter *i* is arranged in and controls the circuit of the primary winding *f*, and the other interrupter *j* is arranged in and controls the circuit of the secondary winding *e*. Also the interrupter *i* is normally closed and the interrupter *j* is normally open. The interrupter *i* consists of a resilient metal blade *k* (Figure 2) secured at one end to a fixed support *m*, and carrying at its other end a contact *n*, the latter being adapted to co-operate with an adjustable contact *o* for controlling the primary winding *f*. The other interrupter *j* consists of a second resilient metal blade *p* secured at one end to the fixed support *m* and carrying a contact *q* adapted to co-operate with another contact *r* for controlling the secondary winding *e*, the latter contact being mount-

ed on but insulated from an intermediate part of the first blade *k*. The second blade *p* is adapted to respond directly to the magnetic attraction of the transformer core *h*, and for this purpose in the example shown in Figure 2 is provided with an iron armature *s* which is situated adjacent to the core, and on which the contact *q* is mounted. Also the second blade *p* is situated between the first blade *k* and the transformer, and the armature *s* is bent and arranged to extend through an aperture *t* in the first blade so that the contact *q* on the armature can co-operate with the corresponding contact *r*, the latter being mounted on the side of the first blade remote from the transformer core *h*. The contacts *n*, *o* are normally closed and the contacts *q*, *r* are normally open. Movement of the second blade *p* by magnetic attraction of the core *h* first causes closure of the contacts *q*, *r*, and is then transmitted through these contacts to the first blade *k*, causing the contacts *n*, *o* to be opened. Consequently this movement of the second blade serves to establish the circuit containing the transformer secondary winding *e* and to interrupt the circuit containing the transformer primary winding *f*.

When current flows from the source of supply *g* through the transformer primary winding *f*, electromagnetic energy is stored in the system, and on interruption of this current the stored energy is converted into current in the transformer secondary winding *e*, the secondary current being supplied to the primary winding *a* of the magneto through the corresponding interrupter *j* which at this instant is in the closed condition.

A condenser *u* may be arranged across the contacts of each of the interrupters *i*, *j*.

The apparatus above described differs from other forms of auxiliary apparatus of the kind above specified, in that a trembler interrupter is associated with each of the transformer windings. By the use of two interrupters operating as above described the auxiliary apparatus can be kept in action for a longer time than usual after the engine has been started, for the reason that there is but little if any interference with the normal action of the magneto when the latter is running at considerable speed. Also the interrupter associated with the secondary winding ensures automatic disconnection of that winding from the magneto when the control switch is opened and the auxiliary apparatus thereby put out of action.

Having thus described my invention what I

claim as new and desire to secure by Letters Patent is:

1. Auxiliary spark ignition apparatus of the kind specified, comprising the combination of a primary winding, a secondary winding, and a pair of trembler interrupters respectively adapted to control the circuits containing the primary and secondary windings.

2. Auxiliary spark ignition apparatus as

claimed in claim 1, in which the primary and secondary windings are mounted on an iron core, and in which the trembler interrupter associated with the secondary winding is responsive to magnetic attraction of the said core, and is adapted to actuate the trembler interrupter associated with the primary winding.

IVAN JACK HULBERT.
